UNITED STATES PATENT OFFICE.

GEORGE H. SCHANCK, OF LIBERTYVILLE, ILLINOIS.

FLYING MACHINE.

1,133,748.

Specification of Letters Patent. Patented Mar. 30, 1915.

Application filed September 12, 1914. Serial No. 861,462.

To all whom it may concern:

Be it known that I, GEORGE H. SCHANCK, a citizen of the United States, residing at Libertyville, in the county of Lake and 5 State of Illinois, have invented certain new and useful Improvements in Flying Machines, of which the following is a specification.

This invention relates to flying machines 10 and its object is to provide a flying machine which is guided in its travel by elevated tracks.

A further object of the invention is to provide a novel switching device for the side 15 tracking of machines.

A further object of the invention is to provide a novel landing platform for the flying machine.

In the accompanying drawings Figure 1 20 is an elevation of the machine and a fragment of the tracks showing the machine resting on a landing platform; Fig. 2 is an end view of Fig. 1 from the right, showing the front end of the machine; Fig. 3 is an 25 elevation similar to Fig. 1 showing the machine in elevated or flying position; Fig. 4 is an end view of Fig. 3; Fig. 5 is an elevation of a fragment of a track supporting a pole showing a track in section; Fig. 6 is an 30 interior view of a fragment of one of the track sections showing a roller-hanger in elevation; Fig. 7 is a perspective view of a portion of a track showing a supporting means therefor; Fig. 8 is an elevation of a 35 portion of the tracks showing a switch for the machine in open position; Fig. 9 is a plan view of Fig. 8; Fig. 10 is an end view similar to Fig. 2 showing a modification.

Referring specifically to the drawings, 40 the flying machine consists of a car 15 of construction suitable for the purpose, having a propeller 16 at the center of each end for forward or rearward propulsion, a propeller 17 mounted on the roof for vertical 45 propulsion, two inclined planes 18 for the lifting of the car during forward movement and a rudder 19 at the forward end of the car. The propellers are operated by electric motors suitably located and controlled 50 from within the car. The planes 18 are of the type employed for aeroplanes and are supported at their forward ends by two rods 20 mounted on the roof of the car, the rear end of the planes being vertically movable 25 by a lever 21 passing downwardly into the car and having suitable controlling means

therein. Thus the planes, which are pivotally connected to the supports 20, may be moved to the proper flying angle by means of the lever 21. The rudder 19 is a flat 60 metal plate supported near the outer end by a rod 22 projecting from the roof of the car. The rod is loosely mounted so that the rudder may be swung laterally from the rear end by means of suitable lever means 23 65 passing through the roof into the car.

The machine is designed to travel between a set of tracks supported by two rows of poles along the line of travel. Each row of poles carries on its inner side two tracks, 70 one being near the top of the poles and the other near the middle. The machine is mounted between the tracks in the following manner: Near the top of one of the poles 24 is a clamp ring 25 to which is pivoted, as 75 indicated at 26, to move in a vertical plane, a U-shaped member 27 extending inwardly of the line of travel. In the ends of the member 27 is rigidly secured at 28 a track 80 consisting of two spaced sections 29 and 30, these being formed in channel shape and meeting in the form of flat sections 31 at the rear. The sections 31 are secured by bolts 31a. The track runs parallel to the line 85 of poles being similarly supported at each pole. The swivel joint at 26 enables the track to swing radially of the same. A coil spring 32 extends out from a clamp ring 33 at the upper extremity of the pole to the track being connected thereto as shown at 90 34. This spring serves to support the track in extended position and prevents it from swinging down against the poles. The inner end of the track has a longitudinal slot 95 34a through which passes a hanger 35 carrying two rollers 36 mounted in tandem relation. The rollers are within the track and are adapted to travel therein, having a medial ridge 37 on their periphery which seats in the slot 34a and thus prevents the center 100 pins 38 of the rollers from coming in contact with the walls of the track. From the hanger 35 a stout rod 39 extends toward the car, having an intermediate adjusting buckle 40 and terminating in a heavy coil 105 spring 41 which is suitably connected near one end of the car at the top. A track 42, similar to the track above described is mounted at about the middle of the row of poles in the same manner, this track also 110 carrying rollers 43 and an inwardly extending rod 44, etc., as the structure near the

5 top of the pole. The rod 44, however, connects to the bottom of the car in vertical alignment with the rod 39, above. Two rods 45 and 46 extend from the opposite end of the car toward the upper and lower tracks in the same manner as the rods 39 and 44. A row of poles similar to that aforementioned also extends on the other side of the machine, and carries two tracks, as the other row of poles. The parts connecting the car with the tracks are here similar to those in the opposite side thereof, and are denoted by like reference numbers. Suitable diagonal brace rods 47 connect the rods 39 and 45, and similar rods 48 connect rods 44 and 46, the object of these rods being to keep the rods connected in parallel relation.

10 With the arrangement above described, it will be seen that the machine in its motion along the line of travel will be supported and guided by the tracks. The springs 41 will be sufficiently heavy to support the weight of the machine and will also serve to equalize the swaying motion of the 15 car.

15 As it is not intended that the tracks support the machine in the manner aforesaid at all times, a support is provided in the form of a landing platform 49. This platform is located between the rows of poles and is supported on the ground by legs 50. Longitudinally of the platform are two parallel rows of rollers 51, these being sunk in the platform nearly flush with the top 20 thereof and being suitably journaled at 52 therein. Underneath the car are two parallel and longitudinal runner boards 53, these being connected to and spaced from the bottom of the car by bow springs 54. When 25 the car is properly positioned on the platform 49, the runner boards 53 rest on the rollers 51. Thus movement of the car on the platform will be free of friction, the runner boards 53 riding the rollers 51. An 30 abrupt descent of the machine upon the platform will be cushioned by the springs 54. On one row of poles is hung an electric trolley wire 55. A trolley pole 56 extends diagonally from the center of that side of the 35 car facing the trolley wire toward the latter, carrying the usual trolley wheel 57. The landing platforms 49 are situated at designated points on the line of travel, to serve as stations or landing places.

35 Before starting on its travel, the machine rests on a landing platform, as shown in Fig. 1. To start the machine in forward direction, the forward propeller 16 is caused to revolve; as the car commences to move 40 the roof propeller 17 is also caused to revolve, this assisting the planes 18 in lifting the machine from the platform. As the machine moves onward, the proper control of the planes 18 will cause it to rise, relieving the tracks of its weight and employing

them for guiding purposes only. When the machine is well along on its way, it will fly in a position similar to that shown in Figs. 3 and 4, being at sufficient height to clear road vehicles, railroad trains or other objects crossing the line of travel. The machine will follow the direction of its tracks at all curves, but to prevent undue strain on the tracks at curves when the machine is traveling at a high speed the rudder 19 will be actuated to assist the machine in rounding such curves. When the line of travel crosses swamps or other low places, the tracks will receive additional support by a cable 58 passing through one or more eye, 59 integral with the track, as shown in Fig. 7. The cable will span the swamp, its ends being suitably secured to the poles on both sides of the swamp. A switching device is also provided, this being for the purpose of side-tracking a machine while an "express" or faster machine is allowed to fly by on the main line.

5 Consulting Figs. 8 and 9, 60 denotes a laterally projecting portion of the landing platform 49, said portion forming a side tracking platform for the car and also having sunk rollers 61, as the main platform 49. The tracks 29 and 42 remote from the platform 60 are severed at 62, one of the severed portions 63 being supported near its end by a pole and carrying an outstanding shelf 64 on which the end of the other severed portion 65 rests. The tracks on the opposite side are also severed at 66, one of the severed sections being formed into a gate by providing vertical rods 67 at the ends thereof and diagonal brace 68 between the rods. The gate thus formed is hung from hinges 69 mounted on a pole 70 carrying the main tracks, said tracks and the gate tracks being suitably joined 71 to allow the swinging of the latter inwardly, as shown. The rods 67 are provided with casters or wheels 72 at the bottom, these rolling on the platform when the gate is swung in and thus serving as an additional support therefor. When a machine approaching in the direction of the arrows is to be side tracked, the track portions 65 are flexed outward by suitable means, as shown in Fig. 9, still resting on the shelves 64, so that the roller-hangers 35 carried by the machine can emerge from the track portions 63. The gate on the switching side is also opened, the corresponding roller-hangers emerging from the track portions 66. The machine now being free of the tracks may be propelled or drawn onto the side platform 60 a sufficient distance to allow the tracks to be again closed.

55 Fig. 10 shows a modification of the means whereby the car is hung from the tracks, the modified form only employing one track on each side of the car. As shown, a triangular member 73 extending from the roller

hanger 35 toward the car carrying at its inner end two spaced tubes 74 and 75 as continuations of the two longer sections of the member 73. On the wall of the car is 5 mounted a plate 75 from which projects two round stems 76 and 77 these being respectively near the top and bottom of the plate and being hinged thereto to allow of their movement in a vertical plane. The 10 stems are adapted to telescope into the respective tubes 74 and 75 aforesaid. Powerful springs 78 and 79 are coiled around the respective tubes 74 and 75, the inner end of the springs being secured to the plates 75 15 and the outer end to the members 73. Thus, the car being in lowered position--resting on the landing platform--the springs 78 will be compressed and the springs 79 expanded, as shown; however, when the machine commences to fly and rises above the tracks, the 20 tension of the springs will obviously become reversed. As the springs are necessarily strong enough to support the weight of the car, they will be amply sufficient for preventing the tilting or swaying thereof. The 25 remaining parts of the system will still be employed except where the modification requires a change. The tracks 29 and 42 are provided with a vertical spacing bar 80 30 midway between each two poles. They are also supported against sagging by diagonal braces 81 extending from the top of the poles toward the middle of the track 42.

I claim:

35 1. An aerial railway comprising a car provided with aerial propellers and lifting planes, and an elevated track on opposite sides of the car, said track being pivotally mounted to swing in a vertical plane, and 40 car suspension means mounted for travel on the track.

45 2. An aerial railway comprising a car provided with aerial propellers and lifting planes, and an elevated track on opposite sides of the car, said track being pivotally mounted to swing in a vertical plane, and 50 flexible car suspension means mounted for travel on the track.

55 3. An aerial railway comprising a car provided with aerial propellers and lifting planes, and an elevated track on opposite sides of the car, suspension arms flexibly connected to opposite sides of the car, and

wheels carried by the outer ends of the arms and mounted for travel on the aforesaid 55 track.

4. An aerial railway comprising a car provided with aerial propellers and lifting planes, an elevated track on opposite sides of the car, said track comprising a hollow 60 member having a slot, and said member being pivotally mounted to swing in a vertical plane, suspension arms flexibly connected to opposite sides of the car and extending through the slot of the hollow member into 65 said member, and wheels carried by the outer ends of the arms and mounted for travel in the hollow member forming the track.

5. An aerial railway comprising a car 70 provided with aerial propellers and lifting planes, an elevated track on opposite sides of the car, said track comprising a hollow member having a slot, and said member being pivotally mounted to swing in a vertical plane, 75 suspension arms flexibly connected to opposite sides of the car and extending through the slot of the hollow member into said member, and wheels carried by the outer ends of the arms and mounted for travel in 80 the hollow member forming the track, said wheels having a peripheral ridge extending into the slot of the hollow member.

6. An aerial railway comprising a car provided with aerial propellers and lifting 85 planes, an elevated track on opposite sides of the car, said track being pivotally mounted to swing in a vertical plane, car suspension means mounted for travel on the track, and spring-supported alighting shoes on the 90 bottom of the car.

7. An aerial railway comprising a car provided with aerial propellers and lifting planes, an elevated track on opposite sides of the car pivotally mounted to swing in a vertical plane, said track having hinged 95 sections for sidetracking the car, and car suspension means mounted for travel on the track.

In testimony whereof I affix my signature in presence of two witnesses.

GEORGE H. SCHANCK.
